(57) **CLAIM**

The ornamental design for a light fixture, as shown and
described.

DESCRIPTION

FIG. 1 is a bottom perspective view of a light fixture in
accordance with my design;

FIG. 2 is a top plan view of the light fixture in accordance with
my design;

FIG. 3 is a bottom plan view of the light fixture in accordance
with my design;

FIG. 4 is a side elevation view of the light fixture in accordance
with my design;

FIG. 5 is an opposite side elevation view of the light fixture in
accordance with my design;

FIG. 6 is a front elevation view of the light fixture in accordance
with my design; and,

FIG. 7 is a back elevation view of the light fixture in accordance
with my design.

The light fixture of FIGS. 1 and 4—7 is shown with a portion
broken away to indicate indeterminate length.

The broken lines showing environmental structure are for
illustrative purposes only and form no part of the claimed
design.

Features of the design include the pattern applied to the article
as shown in the draftsman’s representations.
